LE ROY G. CLARK,
ELECTRIC LIGHTING FIXTURE,
APPLICATION FILED DEC. 27, 1920.

1,426,360.

Patented Aug. 22, 1922.

UNITED STATES PATENT OFFICE.

LE ROY G. CLARK, OF DETROIT, MICHIGAN.

ELECTRIC-LIGHTING FIXTURE.

1,426,360.

Specification of Letters Patent. Patented Aug. 22, 1922.

Application filed December 27, 1920. Serial No. 433,444.

To all whom it may concern:

Be it known that I, LE ROY G. CLARK, a citizen of the United States of America, residing at Detroit, in the county of Wayne 5 and State of Michigan, have invented certain new and useful Improvements in Electric-Lighting Fixtures, of which the following is a specification, reference being had therein to the accompanying drawings.

10 This invention relates to electric lighting fixtures and has for an object the provision of simple, inexpensive, compact and ornamental means for furnishing a direct and unobstructed downward illumination suitable for reading or for lighting the top of 15 a table.

Another object is the provision of a dining room fixture by which the table may be brilliantly lighted by a lamp which is entirely concealed from view except from 20 points between the lamp and the table and whereby the glare of unprotected lights is entirely obviated.

Another object is to provide a combination 25 fixture in which a series of lamps for general lighting of a room are arranged to be used in conjunction with a lamp directed downwardly.

I attain these and other objects by the use 30 in a general lighting fixture of a lens secured in the lower end of a hollow casing formed of an opaque material, preferably metal, the casing having therein a lamp situated so that its rays are directed by the lens 35 within a limited area beneath the lamp.

In the drawing,

Figure 1 is a vertical section of the central portion of the fixture, showing one preferred embodiment of my invention;

40 Fig. 2 is a plan view of the main casting;

Fig. 3 is a perspective view of one of the blocks used to secure a candle bracket to the casting; and

Fig. 4 is an elevation showing the relation 45 of the fixture to a table when used as a dining room light.

A suspension member 1 has an internally threaded bore 2 in which is secured a short nipple 3. On the opposite end of the nipple 50 is secured an open fitting 4 which supports a second nipple 5. A central member formed as a casting 6 having a central opening 7 is mounted on the nipple 5 and maintained in position by a nut 8. Clamped between the support 1 and the casting 6 is an upper casting 55 comprising ornamental casing members

9, 10, and 11, these members being of any desired contour and serving to conceal the supporting tubular members 3, 4 and 5.

It will be seen that the suspension member 1 is secured firmly to the central member 6 by the fittings 3, 4, and 5 holding the casting 6 and the casing members 9, 10 and 11 rigid through the clamping action of the nut 8.

The casting 6 has a series of radial ribs 12 65 adapted to prevent sidewise or rotational movement of blocks 13 which are tapered to fit between two ribs. The block 13 has a bored socket 14 internally threaded to screw upon the end 15 of the tubular bracket 16. 70 Communicating with the socket 14 is a passage 17 for the wires of the electric circuit. A threaded bore 18 in the bottom of the block is provided to receive a screw stud 19 which fastens the block 13 to the casting 6 75 in position between two of the ribs 12. A cover plate 6' assists in securing the blocks 13 in the casting 6.

A hollow casing 20 shown as conveniently made of tubular ornamental sections 21, 22 80 and 23 is secured to the casting 6 by the studs 19, the screw threaded end of the studs passing through holes in a flange 24 of the upper section 21. The sections 21, 22 and 23 may be soldered together. Within the casing 20, 85 upon an adjustable bracket 25 which is secured to the nut 8, is the socket 26 for the lamp 27, the filament of which is supported near the lower end of the casing 20. The end of the casing section 23 is threaded to receive a cap 28 adapted to hold a lens 29 of the ordinary plano-convex type commonly 90 used in portable search lights.

A lens of this type directs the light of a lamp as a conical beam and when viewed 95 from the side does not show as a brilliant source of light. While it provides an efficient illumination within the cone of light, it does not appear as a glaring object to the eyes.

To produce various color effects, discs of glass suitably tinted will be provided, the chosen disc being placed upon the upper surface of the lens 29 as indicated at 39.

By adjusting the lamp 27, the extent of 100 the area of illumination can readily be controlled.

The bracket arms 16 act as supports for lamps (not shown) placed within the globes 105 30 and serving for general illumination of the room. The central member 6 together with its connections to the suspension mem-

ber 1 thus forms a support for the main bracket lamps and for the adjustable bracket lamp and its casing.

The bracket lamps are indicated as arranged in parallel on a circuit controlled by a suitable switch 31 secured on the side of the casing section 22 or in any other convenient location. As shown, the wires 32, 33 and 37, form the circuit for the lamp 27 and this circuit is not controlled by the switch 31. The wires 32, 34, 35, 36 and 37 form the circuit for the lamps in the globes 30, and this circuit is under the control of the switch 31 which may be operated by the button 38 or in any preferred manner. The circuit for the lamp 27 will have another switch located wherever desired. This wiring is merely illustrative, and it is to be understood that the circuits may be arranged to suit the convenience of the user.

The fixture may be shipped with the wires in place in the upper and lower casings and in the arms 16. The blocks 13 will be detached by the removal of the screw studs 19, and the lower casing will be held to the casting 6 by temporary fastening means engaging the studs 19. The passage 17 is cored when the block 13 is cast and it affords a smooth passage for the wires thus obviating the danger of breakage and tearing of the insulation which so frequently occurs in the use of the ordinary fixture body with the rough nipples and other fittings now in common use. To assemble the fixture, the studs 19 will be unscrewed from the temporary fastenings, and the nut 8 unscrewed from the nipple 5. The blocks 13 will then be set between the ribs 12, and the cover plate and upper casing will be clamped upon them by the nut 8. The casing 20 will then be secured to the blocks 13 by inserting the studs 19 and the fixture is ready for use. This simplicity of assembly and the absence of rough and sharp edges to injure the insula-

tion I believe to be important features of my invention.

What I claim is:—

1. An electric fixture comprising a support, a plurality of radially disposed ribs formed in the support, a plurality of blocks adapted to engage with the ribs, each block acting as a support for a lamp bracket, a casing arranged beneath the support and having a flange, and securing means for each block having a screwthreaded portion passing through an opening in the flange and an opening in the support and engaging a screwthreaded aperture in the block. 50

2. An electric lighting fixture comprising a support, a plurality of lamps carried by brackets secured to the support, the bracket for one of the lamps being adjustable to regulate the distance of the lamp from the support, and a casing secured to the support and enclosing the adjustable lamp, the 60 casing having a plano-convex lens mounted in an opening beneath the lamp to direct the light from the lamp within a limited area. 65

3. An electric lighting fixture comprising a support, a plurality of lamps carried by brackets secured to the support, the bracket for one of the lamps being adjustable to regulate the distance of the lamp from the support, and a casing secured to the support and enclosing the adjustable lamp, the 70 casing having a plano-convex lens mounted in an opening beneath the lamp to direct the light from the lamp within a limited area, the lamp within the casing having a separate circuit from that of the other lamps, 75 and a switch mounted on the casing controlling only the circuit of the other lamps. 80

In testimony whereof I affix my signature in presence of two witnesses.

LE ROY G. CLARK.
